PROCESS AND APPARATUS FOR PRODUCING SHEET GLASS

Filed June 11, 1930

UNITED STATES PATENT OFFICE

CARROLL CONE, OF TOLEDO, OHIO, ASSIGNOR TO LIBBEY-OWENS-FORD GLASS COMPANY,
OF TOLEDO, OHIO, A CORPORATION OF OHIO

PROCESS AND APPARATUS FOR PRODUCING SHEET GLASS

Application filed June 11, 1930. Serial No. 460,405.

The present invention relates to a process and apparatus for forming and annealing sheet or plate glass.

In the production of successive sheets of glass by an intermittent rolling operation, it is desirable that the formation of the sheet be performed at a relatively high rate of speed as compared with the speed at which it travels in annealing. This rapid formation of the glass sheet is desirable from both the standpoint of production and quality while the travel of the sheet during annealing is necessarily slow in order to avoid making the annealing apparatus of great length.

The general object of the present invention therefore resides in the provision of a process and apparatus whereby successive sheets of glass may be intermittently formed at a relatively high rate of speed and subsequently annealed while traveling at a relatively slower speed.

Another object of the invention is the provision of a process and apparatus wherein successive sheets of glass are adapted to be intermittently formed at a relatively high rate of speed and carried forwardly at such speed for a suitable distance, after which the sheets are rotated 180° in a manner to effect a reduction in the forward speed of travel thereof, the sheets being subsequently passed at such reduced speed into and through an annealing leer.

A further object of the invention is the provision of means of a novel and improved character for effecting the reduction in the speed of travel of the sheet as it is being carried forwardly, said means functioning to receive the sheet from the forming mechanism at a relatively high speed and deliver it to the annealing leer at a relatively slower speed.

Other objects and advantages of the invention will become more apparent during the course of the following description when taken in connection with the accompanying drawings.

In the drawings forming a part of this application and wherein like numerals are em-

ployed to designate like parts throughout the same,

Fig. 1 is a side elevation, partially in section, of apparatus constructed in accordance with the present invention, and,

Fig. 2 is a section taken substantially on line 2—2 of Fig. 1.

The sheet forming apparatus herein provided comprises a rolling machine including a pair of forming rolls 5 and 6 associated with one end of a tiltable support or receiver 7 and spaced from one another to create a sheet forming pass therebetween. In forming the sheet, a mass or charge of molten glass 8 is deposited upon the receiver 7 from a pot or other suitable receptacle 9 and then passed between the forming rolls which serve to reduce it to a sheet 10 of substantially predetermined and uniform thickness. As it is desirable that the glass sheet be formed at a relatively high rate of speed, the forming rolls 5 and 6 are rotated in a manner to rapidly reduce the mass of molten glass 8 to sheet form.

As the glass sheet leaves the forming rolls, it passes downwardly over an inclined slab 11 and is deflected into the horizontal plane and received upon a runway composed of a series of horizontally aligned rolls 12 from which it passes through the transfer and speed changing apparatus designated in its entirety by the numeral 13, and thence into and through an annealing leer 14. The sheet is supported within and carried through the annealing leer upon a series of horizontally aligned rolls 15 which are driven at a constant relatively slow speed equal to the speed at which it is desired to move the sheet in annealing. Thus, the leer rolls 15 are adapted to be driven, during the formation of the sheet, at a constant relatively slow speed which is materially less than the peripheral speed of the forming rolls 5 and 6.

For example, the leer rolls may be driven at from two to fifteen feet per minute while the sheet is being formed at the rate of from forty to sixty feet per minute. Due to this difference between the forming and annealing speeds, some means must be provided for reducing the forward speed of travel of the sheet after

it has been formed and before it is delivered or passed into the leer. To accomplish this, and also the other objects of the invention, there is provided the transfer and speed changing apparatus 13 referred to hereinabove and which is interposed between the runway 12 and leer 14 for receiving the sheet from the former at one speed and delivering it into the latter at a reduced speed.

The transfer and speed changing apparatus 13 comprises an elongated hollow cylindrical casing or housing 16, closed at each end by a wall 17 provided with a slot 18 through which the sheet 10 may pass. Positioned adjacent each end of the cylindrical housing 16 and encircling the same, preferably in spaced relation thereto, is a relatively wide supporting member 19 connected to said housing by webs 20. The members 19 are supported upon rollers 21 and 22 located at opposite sides of the vertical axis of the housing and being journaled at their opposite ends within fixed supports 23, one only of which is shown in Fig. 1. The housing 16 is adapted to be rotated about its longitudinal axis upon the rolls 21 and 22 by any suitable means such as by the use of one or more ring gears 24 meshing with a pinion 25 mounted upon a drive shaft 26.

Mounted within the housing 16 are two series or sets of horizontally arranged rolls 27 and 28, said rolls being arranged in two superimposed horizontal lines and adapted to receive the glass sheet as it is formed therebetween. The upper and lower sets of rolls 28 and 27 respectively are mounted upon shafts 29 journaled at their opposite ends in the wall of the housing 16, said sets of rolls being preferably spaced from one another a distance slightly greater than the maximum thickness of sheet produced so that when the sheet is being carried along upon either set of rolls, the rolls of the other set will be out of contact therewith. The rolls 27 may be termed the high speed rolls by which is meant that they are adapted to rotate at a relatively high rate of speed equal to the speed of the forming rolls 5 and 6 so that as the sheet is formed it will be carried forwardly upon the rolls 27 at its speed of formation in order to prevent warping and buckling thereof. These rolls 27 are adapted to be driven in unison in any desired manner such as by attaching to one end of each of the roll shafts 29 a worm gear 30 meshing with a worm 31 carried by a line shaft 32, said shaft carrying a sprocket 33 about which is trained a sprocket chain 34, said chain being also trained about a sprocket 35 carried by the shaft of motor 36. Thus, upon operation of motor 36, the shaft 32 will be driven so as to drive all of rolls 27 in unison and at the same speed.

The rolls 28 may be termed the low speed rolls since they are all adapted to be driven at a constant relatively slow speed equal to

the speed of the leer rolls 15, and when the housing 16 is rotated 180° the low speed rolls will be brought into horizontal alignment with leer rolls 15 and will support the sheet thereupon. The rolls 28 may be driven by exactly the same means as the rolls 27 so that a detailed description of the drive therefor is not thought to be necessary.

In the operation of the invention, the housing 16 is first rotated upon rollers 21 and 22 to bring the high speed rolls 27 into horizontal alignment with rolls 12 as illustrated in Fig. 1. A mass or charge of molten glass 3 is then deposited upon receiver 7 and passed therefrom between the forming rolls 5 and 6 where it is reduced to a sheet 10, said sheet passing downwardly over the chute 11 onto the rolls 12 and thence on into the housing 16 upon rolls 27. As pointed out above, the sheet is adapted to be formed at a relatively high rate of speed so that during the formation of the sheet the forming rolls 5 and 6, runway rolls 12, and transfer rolls 27 are all driven at the same relatively high speed. During this period of the operation, the low speed rolls 28 are out of contact with the sheet and can be rotating at their relatively slow annealing speed in order to prevent them from becoming overheated by the heat radiated from said sheet.

After the sheet 10 has been entirely received upon rolls 27, the housing 16 is rotated 180° about its longitudinal axis so that the sheet will be reversed to bring the lower side uppermost and, when this is done, the sheet will then be resting upon the low speed rolls 28. During the turning over of the sheet, it will be apparent that its forward speed of travel will be gradually reduced so that when it is supported upon the rolls 28, it will be moved forwardly at annealing speed into the leer 14 wherein it is carried along upon the rolls 15 at such speed. After the sheet is entirely within the leer, the housing is again rotated 180° to bring the high speed rolls 27 lowermost whereupon the apparatus is in position to receive a second sheet.

In order to prevent lateral shifting movement of the sheet during the time it is being rotated, there may be provided a plurality of vertically disposed rollers 37 arranged at the edges of the sheet between certain adjacent pairs of rolls 27 and 28, these rollers being free to rotate within brackets 38.

It is to be understood that the form of the invention herewith shown and described is to be taken as the preferred embodiment of the same, and that various changes in the shape, size and arrangement of parts may be resorted to without departing from the spirit of the invention or the scope of the subjoined claims.

I claim:

1. The process of producing sheet glass, which consists in first forming the sheet, car- 130

rying the sheet forwardly as it is formed in a generally horizontal direction and to a predetermined location, turning the sheet upside down, and then passing the sheet forwardly into and through an annealing zone.

2. The process of producing sheet glass, which consists in first forming the sheet, carrying the sheet forwardly as it is formed in a generally horizontal direction and to a predetermined location, turning the sheet 180° to bring its bottom surface uppermost, and then passing the sheet forwardly into and through an annealing zone.

3. The process of producing sheet glass, which consists in first forming the sheet, carrying the sheet forwardly as it is formed in a generally horizontal direction and to a predetermined location, rotating the sheet 180° about an axis extending parallel with its direction of movement, and in then passing the sheet forwardly into and through an annealing zone.

4. The process of producing sheet glass, which consists in first forming the sheet, carrying the sheet forwardly as it is formed in a generally horizontal direction upon a series of spaced transverse supporting surfaces, rotating the sheet 180° about an axis extending parallel with its direction of movement, bringing said sheet to rest upon a second series of spaced transverse supporting surfaces, and in then passing the sheet forwardly into and through an annealing zone.

5. The process of producing sheet glass, which consists in first forming the sheet, carrying the sheet forwardly as it is formed in a generally horizontal direction upon a series of spaced transverse supports having rolling contact with said sheet, rotating the sheet 180° about an axis extending parallel with its direction of movement, bringing said sheet to rest upon a second series of spaced transverse supports also having rolling contact with the sheet, and in then passing the sheet forwardly into and through an annealing zone.

6. The process of producing sheet glass, which consists in forming the sheet at a relatively high rate of speed, carrying the sheet forwardly at such speed in a generally horizontal direction and to a predetermined location, turning the sheet 180° to bring its bottom surface uppermost, in reducing the forward speed of travel of the sheet during the turning thereof, and in then passing the sheet forwardly into and through an annealing zone at such reduced speed.

7. The process of producing sheet glass, which consists in forming the sheet at a relatively high rate of speed, carrying the sheet forwardly at such speed in a generally horizontal direction and to a predetermined location, rotating the sheet 180° about an axis extending parallel with its direction of movement, in reducing the forward speed of travel

of the sheet during rotation thereof, and in then passing the sheet forwardly into and through an annealing zone at such reduced speed.

8. The process of producing sheet glass, which consists in forming the sheet at a relatively high rate of speed, carrying the sheet forwardly in a generally horizontal direction at such speed upon a series of spaced transverse supporting surfaces, rotating the sheet 180° about an axis extending parallel with its direction of movement, in bringing the sheet to rest upon a second series of spaced transverse supporting surfaces, in effecting a reduction in the forward speed of travel of the sheet during rotation thereof, and in then passing the sheet forwardly into and through an annealing zone at such reduced speed.

9. The process of producing sheet glass, which consists in forming the sheet at a relatively high rate of speed, carrying the sheet forwardly in a generally horizontal direction at such speed from a series of spaced transverse supports having rolling contact with the sheet, rotating the sheet 180° about an axis extending parallel with its direction of movement, in reducing the forward speed of travel of the sheet during rotation thereof and bringing it to rest upon a second series of spaced transverse supports also having rolling contact with the sheet, and in then passing the sheet forwardly into and through an annealing zone at such reduced speed.

10. In sheet glass apparatus, means for receiving a newly formed sheet of glass from sheet forming mechanism and delivering it into an annealing leer including conveying means for receiving the sheet thereupon from the sheet forming mechanism, a second conveying means for delivering the sheet into the annealing leer, and means for rotating the first conveying means to turn the sheet upside down and bring it to rest upon said second conveying means.

11. In a sheet glass apparatus, means for receiving a newly formed sheet of glass from sheet forming mechanism and delivering it into an annealing leer including conveying means for receiving the sheet thereupon from the sheet forming mechanism, a second conveying means mounted above the first conveying means and adapted to deliver the sheet into the annealing leer, and means for rotating said conveying means as a unit to transfer the sheet from the first conveying means onto the second conveying means.

12. In sheet glass apparatus, means for receiving a newly formed sheet of glass from sheet forming mechanism and delivering it into an annealing leer including conveying means for receiving the sheet thereupon from the sheet forming mechanism, a second conveying means mounted above the first conveying means and adapted to deliver the sheet into the annealing leer, and means for

rotating said conveying means as a unit 180° about an axis extending longitudinally thereof to transfer the sheet from the first conveying means onto the second conveying means.

13. In sheet glass apparatus, means for receiving a newly formed sheet of glass from sheet forming mechanism and delivering it into an annealing leer including a series of 10 rolls for receiving the sheet thereupon from the sheet forming mechanism, a second series of rolls arranged above the first series and adapted to deliver the sheet into the annealing leer, and means for rotating said series 15 of rolls as a unit to transfer the sheet from the first series of rolls onto said second series of rolls.

14. In sheet glass apparatus, means for receiving a newly formed sheet of glass from 20 sheet forming mechanism and delivering it into an annealing leer including two superimposed sets of rolls for receiving the sheet therebetween, and means for rotating said sets of rolls as a unit to transfer the sheet 25 from one set of rolls to the other.

15. In sheet glass apparatus, means for receiving a newly formed sheet of glass from sheet forming mechanism and delivering it into an annealing leer including a housing, a 30 series of rolls arranged therein for receiving the sheet thereupon from the sheet forming mechanism, a second series of rolls arranged above the first series and adapted to deliver the sheet into the annealing leer, and means 35 for rotating said housing to transfer the sheet from said first series of rolls to said second series of rolls.

16. In sheet glass apparatus, means for receiving a newly formed sheet of glass from 40 sheet forming mechanism and delivering it into an annealing leer including a housing, a series of rolls arranged therein for receiving the sheet thereupon from the sheet forming mechanism, a second series of rolls arranged 45 above the first series and adapted to deliver the sheet into the annealing leer, means for rotating said housing to transfer the sheet from said first series of rolls to said second series of rolls, means carried by the housing for 50 driving the first series of rolls, and means also carried by the housing for driving the second series of rolls independently of the first series.

17. In sheet glass apparatus, means for receiving a newly formed sheet of glass from 55 sheet forming mechanism at a relatively high rate of speed and delivering the same into an annealing leer at a relatively slower speed, including conveying means for receiving the sheet thereupon from the sheet forming mechanism, means for driving said conveying means at a relatively high rate of speed, a second conveying means for delivering the sheet into the annealing leer, means for driving said second conveying means at a relatively slower speed, and means for rotating

the first conveying means to bring the sheet to rest upon said second conveying means.

18. In sheet glass apparatus, means for receiving a newly formed sheet of glass from sheet forming mechanism at a relatively high rate of speed and delivering the same into an annealing leer at a relatively slower speed including a series of rolls for receiving the sheet thereupon from the sheet forming mechanism, means for driving said rolls at a relatively high rate of speed, a second series of rolls mounted above the first series and adapted to deliver the sheet into the annealing leer, means for driving said second series of rolls at a relatively slower speed, and means for rotating both series of rolls as a unit about an axis extending parallel with the direction of movement of the sheet for transferring the sheet from the first series of rolls onto the second series of rolls.

19. In sheet glass apparatus, means for receiving a newly formed sheet of glass from sheet forming mechanism at a relatively high rate of speed and delivering it into an annealing leer at a relatively slower speed including an elongated cylindrical housing, two superimposed sets of rolls arranged within said housing and extending in two spaced parallel lines longitudinally thereof for receiving the glass sheet therebetween, means for driving one set of rolls at a relatively high rate of speed, means for driving the other set of rolls at a relatively slower speed, and means for rotating the housing about its longitudinal axis to transfer the sheet from the high speed rolls onto the low speed rolls.

20. In sheet glass apparatus, means for receiving a newly formed sheet of glass from sheet forming mechanism at a relatively high rate of speed and delivering it into an annealing leer at a relatively slower speed including an elongated cylindrical housing, two superimposed sets of rolls arranged within said housing and extending in two spaced parallel lines longitudinally thereof for receiving the glass sheet therebetween, means for driving one set of rolls at a relatively high rate of speed, means for driving the other set of rolls at a relatively slower speed, means for rotating the housing about its longitudinal axis 110 to transfer the sheet from the high speed rolls onto the low speed rolls, and means for preventing lateral shifting movement of the sheet relative to the rolls during rotation of said housing.

Signed at Toledo, in the county of Lucas and State of Ohio, this 6th day of June, 1930.

CARROLL CONE.
